Application September 3, 1938, Serial No. 79,739

Term of patent 3½ years

To all whom it may concern:

Be it known that I, Alice Engel, a citizen of the United States of America, residing in New York city, in the Borough of Manhattan, county and State of New York, have invented a new, original, and ornamental Design for a Dress, of which the following is a specification, reference being had to the accompanying drawing, forming part thereof, wherein,

Figure 1 is a front view of a dress showing my new design.

The characteristic feature of my design resides in the combination on the dress disclosed of the particular lace yoke and the scalloped girdle section in association with the lace trimmed sleeves and pockets, substantially as shown.

I claim:

The ornamental design for a dress, substantially as shown and described.

ALICE ENGEL.
